UNITED STATES PATENT OFFICE.

VINCENT S. BLOOMHALL, OF CONSHOHOCKEN, PENNSYLVANIA.

PUDDLING AND HEATING FURNACE.

SPECIFICATION forming part of Letters Patent No. 240,081, dated April 12, 1881.

Application filed March 12, 1880. (No model.)

To all whom it may concern:

Be it known that I, VINCENT S. BLOOMHALL, a citizen of the United States, residing in Conshohocken, Pennsylvania, have invented certain Improvements in Puddling and Heating Furnaces, of which the following is a specification.

My invention relates to combined furnaces and elevated boilers in which steam is generated by the waste part of the furnaces; and my invention consists in combining the elevated plates which carry the boiler and the brick-work appertaining to the same, with flattened pipes placed on the plates within the flue beneath the boiler, so that a plentiful supply of heated air for use in connection with the furnace may be obtained, and so that the pipes may diminish the heat and add to the comfort of the operatives on the floor below.

In the accompanying drawings, Fig. 1 is a side view of a puddling-furnace and steam-boiler, the flues, air-heating pipes, and chimney being in section; Fig. 2, a sectional plan on the line 1 2; Fig. 3, a transverse section on the line 3 4; Fig. 4, the same showing a modified arrangement of air-heating pipes, and Fig. 5 a perspective view of a section of the air-heating pipes.

A is an ordinary puddling-furnace, and B a steam-boiler mounted in suitable brick-work, which is built on cast-iron plates *w*, the whole being supported by columns *E*, this combination of a puddling or heating furnace with a steam-boiler being commonly adopted in rolling-mills.

The vertical flue *G*, at the rear end of the furnace, communicates with the chimney *H* through a horizontal flue, *I*, between the boiler and the plates, so that steam may be generated by the waste products of combustion passing from the furnace through the said flue *I*.

In modern puddling and heating furnaces heated air is frequently used, both for introduction into the ash-pit and into the fire-chamber above the fuel, and various plans have been adopted for heating the air by the waste products of combustion from the furnace; but when the latter is combined with a steam-boiler difficulty has been experienced in heating the air without seriously detracting

from the steam-generating properties of the said waste products. In order to obviate this difficulty, I place on the plates *w*, which form the bottom of the horizontal flue *I*, air-pipes *K K'*, which I prefer to make of sheet-iron or terra-cotta, and in sections (Fig. 5) fitted together. Air is admitted to the pipe *K* at *n*, and, after traversing this pipe, passes through the branch *m* into the pipe *K'*, from which it is discharged through the outlet *p*. Two additional pipes may be arranged, one on each side of the flue *I*, close to the brick-work, as shown in Fig. 4, but these are not essential to my invention. The pipes are flattened and placed directly on the plates *w*, for two reasons: first, because they may not materially lessen the depth of the flue of a combined furnace and boiler which has already been erected; and, second, because they cover, or nearly cover, the plates, and maintain the same at a comparatively low temperature, so as to prevent that radiation of heat which is so oppressive to the operatives on the floor below when the upper surface of the plates is exposed to the action of the waste products of combustion.

As before remarked, the structure to which my invention is applied has long been in use in rolling-mills. Air-heating passages have also been formed below the lower flue of a steam-boiler, and blasts of air have been introduced into such lower flues, hence I lay no broad claim to any of these features; but

I claim as my invention—

The combination, in a combined puddling or heating furnace and elevated boiler, of the plates *w*, on which the boiler and brick-work are mounted, with flattened air-heating pipes placed directly on the said plates, forming the bottom of the flue *I* beneath the boiler, and having inlet and discharge branches, whereby air is caused to circulate through said flattened pipes, all substantially as set forth.

In testimony whereof I have signed my name to this specification in the presence of two subscribing witnesses.

VINCENT S. BLOOMHALL.
